UNITED STATES PATENT OFFICE

165,967

SCRIBER

Fred N. Day, Missoula, Mont.

Application August 10, 1951, Serial No. 16,231

Term of patent 14 years

(Cl. D93—2)

To all whom it may concern:

Be it known that I, Fred N. Day, a citizen of the United States, residing at Missoula, in the county of Missoula and State of Montana, have invented a new, original, and ornamental Design for a Scriber, of which the following is a specification, reference being had to the accompanying drawing, forming part thereof.

Figure 1 is a side elevational view of a scriber, showing my new design;

Figure 2 is an end view thereof;

Figure 3 is an underside plan view; and

Figure 4 is a perspective view of the same.

I claim:

The ornamental design for a scriber, as shown.

FRED N. DAY.
